UNITED STATES PATENT OFFICE

WILLIAM H. BANGS, OF ATLANTA, GEORGIA, ASSIGNOR TO ROSS L. CAMPBELL, OF ATLANTA, GEORGIA.

COIL-TAPING MACHINE.

SPECIFICATION forming part of Letters Patent No. 715,941, dated December 16, 1902.

Application filed April 11, 1902. Serial No. 102,364. (No model.)

To all whom it may concern:

Be it known that I, WILLIAM H. BANGS, a citizen of the United States, residing at Atlanta, in the county of Fulton and State of Georgia, have invented certain new and useful Improvements in Coil-Taping Machines, of which the following is a specification.

The invention relates to improvements in coil-taping machines, and has for its object 10 the provision of a machine which will wind tape from its reel upon an armature, field, transformer, and like coils in an even and speedy manner, thus dispensing with extra tools for this purpose and saving a great 15 amount of time where such operation is done by hand.

Another object of my invention is the provision of a machine of this character which is simple, durable, and comparatively inexpensive in construction and which is thoroughly efficient and practical in use.

To attain the desired objects, the invention 25 consists of a coil-taping machine embodying novel features of construction and combination of parts, substantially as disclosed herein.

In the accompanying drawings, Figure 1 is a side elevation of the entire machine. Fig. 2 is a section taken on line $\alpha\alpha$ of Fig. 1. Fig. 3 is a top plan view thereof. Fig. 4 is a vertical sectional view of the pedestal or support, with the removable coil-holding device in position. Fig. 5 is an enlarged detail view of the tension device for the tape-spool.

Referring by numeral to the drawings, the 35 numeral 1 designates the pedestal or support, which is provided with the base 2, to be secured to any suitable platform, and is substantially the shape of an inverted V in elevation. Carried by the pedestal or formed 40 integral with its apex is a circular ring or hollow bearing 3, which is provided with the two parallel peripheral flanges or rims 4, a slot 5 being provided in the ring and flanges for the purpose of the admission of a coil to be taped. 45 Adapted to fit stationarily, yet removably, in the opening or central space of the ring is a disk 6, which is provided with a central circular recess 7 and the V-shaped recess 8, leading thereto, these recesses being used for the 50 reception of the coil while the same is being wound with tape. Adapted to fit on the ring

and revolve therearound between the flanges is the large disk or wheel 9, which has the grooved periphery 10 and is provided with a channel or long opening 11, extending from its periphery toward its center, this channel or opening being adapted to allow the coil to be wound to be inserted, so as to rest upon the disk 6. In order that this channel or opening will be closed and there be no break in the periphery as the wheel is being revolved by the pulley or motor-wheel 12, I provide the hinged segment 13, which is locked in position by means of the catch 14. Secured upon the outer face of the large wheel or disk near its innermost edge is the tension-wheel or idler 15, which is adjustably mounted so as to give the proper tension to the tape as it passes from the tape-carrying reel 16 to the coil. This tape-reel is spring-tensioned, so that the tape 70 is always allowed to be drawn therefrom taut, all slack being taken up by the reel and also the idler.

In Fig. 5 I have shown a device for giving the proper tension to the tape as it leaves the reel, and this consists, substantially, of the long slot 17, in which is slidably mounted the shaft 18, carrying the guide-wheel 15. A spring 20 is employed to normally push the shaft outward, and thus allow all slack to be 80 taken up and insure the even supply of the tape to a coil.

From this description, taken in connection with the drawings, the operation of my improved coil-taping machine is readily understood and its numerous advantages fully appreciated; but, briefly stated, the operation is as follows: The hinged segment is released, and as the channel 11 is in line with the slot of the ring a coil is readily slid therethrough 90 and placed in position upon the bearing-disk 6. The hinged segment is now closed and fastened, and as the tape is in proper position to be fed to the coil the motor is set in operation and the wheel 9 is revolved. As it 95 revolves the tape is wound from the reel, which makes a complete revolution around the coil, which remains stationary. In order to insure an even winding of the tape, the coil is fed laterally by an attendant.

It is evident that I provide a coil-taping machine which will place the tape evenly and

tightly upon coils and the like and will save much time and labor in doing so, thus producing a thoroughly efficient and practical machine.

5. What I claim as new, and desire to secure by Letters Patent, is—

1. In a machine of this character, the combination of a suitable support, means for holding a coil stationarily carried by and in 10 the center of the support, a disk revolvably mounted upon the support and surrounding the holding means, and means for carrying tape to be wound upon the coil carried by the disk.

15. 2. In a machine of this character, the combination of a support, a disk revolvably mounted upon said support, means for holding a coil carried by and in the center of the support, the body of the disk and the holding means 20 being in substantially the same plane, a tape-supplying means carried upon the outer face of and revolvably with the disk on the same face, and tension devices for allowing the tape to be fed taut carried by the disk.

25. 3. In a coil-taping machine, the combination of a support, and outwardly-extending flanged bearing carried thereby, a coil-holding device mounted stationarily yet removably in the bearing, a disk revolvably mounted 30 upon the bearing-ring between the flanges, and means for carrying tape carried by the disk.

40. 4. In a coil-taping machine the combination of a support, a hollow flanged bearing carried thereby, a coil-holding device mounted 35 in the hollow of the bearing, a disk revolvably mounted upon the bearing, tension devices mounted upon the disk, an idler carried upon one of the devices, and tape-carrying means carried by the other.

45. 5. In a coil-taping machine, the combination of a support, a hollow flanged bearing carried thereby, a coil-holding device mount-

ed in the bearing, a large disk provided with a long channel from its periphery to its center mounted upon the bearing, and tape-supplying means carried by and revolvble with the disk; said bearing being provided with a slot to allow a coil to be placed through the channel of the disk to the coil-holding device. 50

6. In a coil-taping machine, the combination, of a support stationarily yet removably mounted, means to hold a coil carried thereby, a disk revolvably mounted upon the support having a grooved periphery, means to allow 55 a coil to be inserted in its proper place to be wound, and tape-supplying means carried by the disk.

7. In a coil-taping machine, the combination of a support, a hollow flanged bearing carried thereby, a coil-holding device mounted in the hollow of the bearing, a disk having a grooved periphery to receive a power-transmitting means revolvably mounted upon the bearing, tension devices mounted upon 65 the disk, an idler carried upon one of the devices, and tape-carrying means carried by the other.

8. In a coil-taping machine, the combination of a pedestal having a base, a bearing-ring mounted at the apex of the pedestal and projecting outward therefrom, a disk revolvably mounted upon the bearing-ring, a coil-holding device mounted within the bearing-ring, means for supplying tape to the coil 75 mounted upon the outer face and revolvble with the disk, and a tension device mounted upon the disk upon the same face as tape-supplying means.

In testimony whereof I affix my signature 80 in presence of two witnesses.

WILLIAM H. BANGS.
